HARNESS MOTION

Edward C. Nichols, Upton, Mass., assignor to
Draper Corporation, Hopedale, Mass., a cor-
poration of Maine

Application November 18, 1944, Serial No. 564,011

8 Claims. (Cl. 139—89)

1

The present invention relates generally to shedding mechanisms for looms and, as illustrated herein, relates more particularly to an improved harness spring mechanism.

It is conventional practice in modern high speed looms to move the loom harnesses positively in one direction and to retract or move the harnesses in the other direction by the use of helical springs. Such springs have not been generally satisfactory since they break and it is difficult to make the necessary adjustments to vary the spring tension to provide for widely varying conditions of operation. Relatively small variations in spring tension may be made, but if large increases or decreases in tension are to be made, it is necessary to substitute heavier or lighter springs as the case may be.

One object of the present construction, accordingly, is to provide a harness spring mechanism by the use of which the above objections will be overcome. To this end and in accordance with one feature of the invention, means are provided for adjusting the spring tension of each harness spring individually within relatively wide limits and means for adjusting the tension of the harness springs collectively within relatively narrow limits to obtain precisely the tension required. As illustrated, flat spiral clock type springs are provided which are anchored at one end to a support and have their other end arranged to enter recesses or slots in the hub of a sheave to obtain approximately the tension desired in each spring member. Further collective adjustment is accomplished by angular adjustment of the supporting frame for the harness spring members. It is apparent from the above that the harness spring tension may be accurately varied between wide limits.

Other objects of the invention are generally to improve upon the construction and operation of looms.

With the above and other objects and features in view, the invention will now be described with particular reference to the accompanying drawing in which—

Fig. 1 is a view in front elevation of a portion of a loom having a preferred embodiment of the invention applied thereto;

Fig. 2 is a detail view in front elevation of the harness spring assembly;

Fig. 3 is a perspective view, partly in section, showing the adjusting mechanism;

Fig. 4 is a detail view similar to Fig. 2 but showing the parts in rear elevation;

2

Fig. 5 is a view in side elevation of the spring assembly; and

Fig. 6 is a view in elevation of part of the positive pull down means.

In the drawings, only a portion of a loom is shown. The parts not shown are of conventional construction and need not be described or shown herein since they form no part of the present invention.

10 The loom to which the present invention is applied is provided with cam mechanism for positively moving the harness 10 downwardly and with spring retractor means 12 for moving the harnesses 10 in the opposite direction. Such positive means includes treadles 13 which are operated by the usual harness cams (not shown) to depress the harnesses 10. The treadles 13 are each connected to the bottom bar 15 of a respective harness frame by the usual adjustable strap 17. The spring means 12 is connected to the left hand end of the harness frame 10 by a strap 14 which passes over a sheave 16 mounted on a support 18. Screws 20 secure the support 18 to an arch connection 22. The lower end of the strap 14 is provided with a series of holes in which a hook 24 may be inserted for adjustment, the lower end of the hook 24 fitting into a screw eye 26 projecting upwardly from the top bar 28 of the harness frame 10. A strap 30 is also connected to the spring means 12 and passes over another sheave (not shown) and is connected to the right hand end of the harness frame 10 by a hook and eye (not shown) which are similar to the hook 24 and the eye 26 at the left hand side of the frame 28.

35 The spring means 12 includes a spiral spring 32 formed of flat ribbon-like material. One end of the spring 32 is hooked and caught under a rod 34 supported in front and rear supporting frames 36 and 38, respectively. The supports 36 and 38 are connected together and supported on a stub shaft 40 which passes through a hole drilled in the upper end of the left hand arch end 42 and to which the left hand end of the arch connection 22 is secured. The shaft 40 is held in position by a set screw 44 passing through the arch end 42. Each of the supports 36 and 38 is generally in the form of an inverted T, one of the legs of each of which has an opening to receive the rod 34. Set screws 46 and 48 secure the rod 34 in position on the front and rear supports, respectively. The other ends of the cross bars of the T's are also interconnected by a rod 50 which is secured by set screws 52, 54 to the front and rear support frames, respectively.

The other end 55 of the spring 32 is also hooked and is inserted in one of a series of slots 56 formed in a hub member 58 formed integrally on a sheave 60. Each sheave 60 (including its hub 58) oscillates on stub shaft 40 independently of the other sheaves. The hub member 58 and the sheave 60 are formed preferably of cast iron although other materials may be used if so desired. The sheave 60 is formed with a forwardly projecting generally cylindrical lip 62 which is 10 slightly wider than the spiral springs 32. The lip 62, adjacent to its outer end, is provided with a series of spaced threaded holes 64 which are arranged to receive a screw 66 passing through a hole formed in one end of a harness strap 68. 15 The other end of the harness strap is secured to the straps 14 and 30 by a hooked member 70.

The spring 32 is so wound that it rocks the sheave 60 in a counter-clockwise direction. The spring 32 is placed under tension by winding it in clockwise direction and inserting the inner hooked end 55 in the proper slot 56. If greater tension is desired, the hooked end can be moved further in a clockwise direction and the hooked end 55 inserted in the nearest slot 56. Each 25 sheave 60 in the series is placed under substantially the same tension as the sheaves 60 are assembled, one after the other on the shaft 40. Further and closer adjustment of the tension on each spring 32 can be obtained by shifting the screw 66 in the spaced holes 64 in the lip 62. These holes 64 are spaced apart an angular distance substantially less than the angular distance between two adjacent slots 56. Thus, relatively 30 close adjustment of each individual spring 32 is obtained. Excessive counter-clockwise movement of each sheave 60 is prevented by a stop rod 72 passing through openings in the upper end portions of the front and rear support frames 36 and 38 respectively. Each sheave is provided 35 with an opening 74 through which the rod 72 passes. Thus, when the strap 68 is disconnected from the straps 14 and 30, the sheave 60 is free to rotate in a counter-clockwise direction until the inner edge of the frame of the sheave 60 40 strikes the rod 72.

It is desirable to provide spacers 76 between each of the sheaves 60. These spacers 76 are provided with openings through which the rods 34 and 50 pass and which support the spacers 76 in 50 position. Each spacer 76 is provided with a spring retainer 78 having a curved surface coinciding with the curve of the end 80 of the spring 32. The retainer 78 is cast as a part of the spacer 76 and close to the rod 34 so that the spring 32 55 can be inserted therebetween. A felt strip 80 is preferably provided and cemented to the member 78 and acts to absorb vibration and to prevent undue wear on the spring 32. Each spacer 76 is also provided with a spring vibration dampening roll 82 which is so located that vibrations having an amplitude greater than the spacing between the adjacent convolutions of the spring are 60 dampened. Thus, adjacent convolutions are prevented from touching each other and thus wear, which might be produced by rubbing of adjacent convolutions, is prevented. The roll 82 is mounted on a pin 84 and is free to rotate.

After the sheaves 60 and the springs 32 have been assembled on the shaft 40, the sheaves 60 70 are prevented from lateral movement by washers 86 and cotter pin 88. Lateral movement of the spacer bars 76 is prevented by collars 90 locked to the rod 34 by a set screw 92. After the parts 75 have been thus assembled, it may be desirable to

adjust the tension of the springs 32 still further and this is readily accomplished by rotating the entire assembly about the shaft 40 and locking the assembly in position by tightening a lock nut 94 against a hub 96 formed on and as part of the rear support frame 38. A bolt 98 passes through a curved slot 100 in the hub portion 96 of frame 38 which limits the adjustment which may be made.

The term "spiral" as used herein to describe springs 32 is used in its limited sense, excluding helical tension springs.

The drawings show only two spring means 12 but it is evident that the number of means 12 must correspond to the number of harnesses used in the loom.

Having thus described my invention, what I claim as new and desire to secure by Letters Patent of the United States is:

1. In a loom, a harness frame, means for moving the frame in one direction, a rotatable member mounted above said frame, flexible connections between the member and the harness frame, a spiral spring for moving the rotatable member and the harness frame in the opposite direction, a hub on said rotatable member having a plurality of slots therein selectively receiving the inner end of said spring, and means angularly adjustable relatively to said rotatable member to which the outer end of the spring is secured.

2. In a loom, a harness frame, means for moving the harness frame in one direction, spiral spring means for moving the harness frame in the other direction, a rotatable member mounted above said harness frame, strap connections between the frame and the rotatable member, a hub on said rotatable member having a plurality of slots therein in which the inner end of said spring means is selectively positioned, an adjustable support, means on said support to which the outer end of said spring means is secured, and means for securing said support in adjusted position.

3. In a loom, a harness frame, means for moving the harness frame in one direction, a flat clock-type spring for moving the harness frame in the other direction, a rotatable member mounted above said harness frame, strap connections between said member and said harness frame, a hub on said rotatable member having a plurality of slots therein in which one end of said spring is selectively positioned, a rotatably mounted support, a member on said support to which the other end of said spring is secured, and means for locking said support in adjusted position.

4. In a loom, a plurality of harness straps, means for moving the straps in one direction comprising a plurality of spiral springs, means for individually adjusting the tension of each of said springs, and means for simultaneously varying the tension of all of said springs.

5. In a loom, a plurality of harness straps, means for moving the harness straps in one direction comprising a plurality of flat spiral springs, independently rotatable members to which one end of each of said springs is connected, means connecting each of said straps to a respective one of said rotatable members, means on each of said members for independently adjusting the tension of the spring connected thereto, and means for simultaneously adjusting the tensions of said springs.

6. In a loom, a plurality of rotatable members each having a plural-slotted hub, a plurality of

harness straps, means connecting each of said straps to a respective one of said rotatable members of movement of the member in one direction, a plurality of spiral springs, one for each of the rotatable members and associated therewith, each spiral spring at one end thereof being engaged in a selected slot of a respective rotatable member to rotate the member in a direction opposite to said one direction with a selected degree of torque, and means for anchoring the other end of each of said springs, the last said means being movable relatively to the rotatable members for simultaneously adjusting the tension of all of said springs.

7. In a loom, a plurality of independently rotatable sheaves each having a plural-slotted hub and a lip provided with a plurality of fastener receiving holes, a plurality of harness straps, a plurality of fasteners one for each sheave and fitted in a selected one of said holes and attaching an individual one of said harness straps to the respective one of said sheaves for movement of the sheave in one direction, a plurality of spiral springs one for each of the rotatable sheaves and associated therewith, each spiral spring at one end thereof being engaged in a selected slot of the associated sheave to rotate the sheave in a direction opposite to said one direction with a selected degree of torque, means to which the other end of each of said springs is anchored, and a bracket in which said last named means is supported, said bracket being movable

into various positions to simultaneously adjust the tension of all of said springs.

5 8. In a loom, a harness frame, means for moving the harness frame in one direction, spiral spring means for moving the harness frame in the other direction, a rotatable member mounted above said harness frame, flexible connections between the harness frame and the rotatable member, a hub attached for rotation with said rotatable member and having a plurality of slots within any selected one of which the inner end of said spring may be connected, and means angularly adjustable relatively to said rotatable member for adjustably positioning the outer end of said spiral spring and means to lock said last mentioned means in an adjusted position.
